UNITED STATES PATENT OFFICE.

RUDOLF EICHENBERGER, OF ZURICH, SWITZERLAND.

DEVICE FOR PRODUCING PERMANENT UNDULATION.

Application filed September 11, 1922. Serial No. 587,412.

To all whom it may concern:

Be it known that I, RUDOLF EICHENBERGER, citizen of the Republic of Switzerland, residing at Rennweg 35, Zurich, Switzerland, have invented a certain new and useful Improvement in a Device for Producing Permanent Undulation, of which the following is a specification, reference being had therein to the accompanying drawing.

10 In order to produce an undulation effect on hair and particularly on women's hair that remains for a long time, it is known to subject the latter to a treatment in which single plaits of hair are moistened with a liquid and are wound around sticks which are then placed inside electrically heated tubes hung up on wires supplying the electric current. By this treatment a drying of the hair and a permanent undulation of 20 the latter results.

According to the present invention the device for producing permanent undulation comprises a curl-stick shaped as a tube for winding the hair thereon and a heating cylinder adapted to receive the curl stick, a cord being fixed with its one end to said curl stick, the other end of the cord passing through the hollow curl stick and forming a loop in which the end of the plait of hair 25 can be clamped. A second tube may be loosely mounted inside the curl-stick, a spring being provided which tends to pull a conical portion at one end of the inner tube into the outer tube and to prevent there- 30 by a turning motion of the two tubes relatively to each other. The curl-stick may also be provided with laterally projecting members which may be detachably arranged, and around which the plaits of hair may be 35 wound in order to produce a special wave shape.

Two constructional examples of the device according to the invention are illustrated on the accompanying drawings, in 40 which:

Fig. 1 shows the heating cylinder in a longitudinal section,

Fig. 2 shows part of the heating cylinder in elevation,

Fig. 3 is a section along line III—III of Fig. 1,

Fig. 4 is a section along the line IV—IV of Fig. 1,

Fig. 5 is a plan view of the heating cylinder, some parts being partly removed,

Fig. 6 shows a curl-stick according to a

first constructional example in a longitudinal section, the spring being compressed,

Fig. 7 is a side view of the curl-stick with the spring released,

Fig. 8 shows the curl-stick after hair has been wound upon it,

Fig. 9 shows on an enlarged scale a curl-stick according to a second constructional example,

Fig. 10 is a longitudinal section and

Fig. 11 is a side view of the curl-stick according to Fig. 9.

Referring now to the heating cylinder illustrated in Figs. 1-5, 1 denotes an inner tube having apertures 2 approximately in the middle of its length, so that the upper and the lower part of tube 1 are connected together by narrow bridge-parts 3. Around the upper part a heating body 4 is arranged and around the lower part a heating body 5 is provided, the heating effect of the heating body 4 being weaker than that of the heating body 5, caused for instance by a lesser number of windings of the heating wire coil. 6 denotes a cover or shell. Between the latter and the heating bodies there is the heating space 7. This space 7 is in its lower part in connection with the surrounding air by means of air inlet ports 8 and in its upper part by means of air exit ports 9. The cover is provided with two apertures 11 leaving narrow bridge parts 12 of the solid material; the apertures 11 being arranged between the heating body 4 and the switch 10 made of an insulating material, for instance of fibre. The switch 10 is of a known construction; by turning the pins 13 around the axis of the heating cylinder through a determined angle the current is cut in and out. A plurality of heating cylinders are suspended in a known manner from the wires 14 supplying the electric current in order to treat several plaits of hair simultaneously.

The curl-stick according to Figs. 6-8 comprises an outer tube 14, in which an inner tube 15 is loosely inserted. A compression spring 16 which bears with its one end against a collar 17 on the inner tube 15 and with its other end against the tube 14 tends to pull the inner tube into the outer tube 14 in the direction of the arrow shown in Fig. 7. The inner tube is provided at its one end with a conical portion 18, the latter being partly pulled into the tube 14 by the pressure of the spring 16, as is shown in

Fig. 7. When the conical portion 18 bears against the outer tube 14 it acts like a cone-friction coupling and any turning of the tubes 13 and 14 relatively to each other is prevented. If a pressure is exerted on the inner tube in the direction of the arrow shown in Fig. 6 the cone coupling is put out of action and the tube 14 may be turned on tube 15. One end of a cord 19 is fixed to the conical part 18, the other end 20 of the cord passes through the tube 15, in this manner a loop 21 is formed.

The afore described device is worked as follows:

15 The loop 21 is placed around a plait of hair 22 near the head and is clamped by pulling the loop together. Thereafter the plait of hair is wound around the curl-stick in the manner illustrated in Fig. 8 and 20 the upper end 23 of the plait is fastened by means of the end 20 of the cord, the cord 20 being thereby clamped in between the coils of the spring 16. In order to still further tighten the windings of the plait of 25 hair on the tube 14 pressure is applied to the collar 17 so that the tube 14 can be turned relatively to the tube 15, which is held stationary, by this turning motion the plait of hair is tensioned. Then the wound hair is covered 30 by the wadding 24 being wound around it and further by an envelope of paper 25, which envelope is tied together at its lower end 26, the upper end being left untied so that any vapour can escape. Now the heating 35 cylinder is placed over this enveloped part of the hair on the head, the envelope filling up the inner pipe 1. Thereafter the current is switched in and the hair thus treated is subjected to a drying action for 40 some time.

The circulation of air through the apertures 8 and 9 presents the advantage, that the cover 6 does not become so hot as to cause a burning in case the cover comes inadvertently into touch with the head. The heating effect by means of the heating body 4 is weaker than that of the heating body 6, as the hair is in its natural state already dryer at its ends than at its roots. For this 45 reason the apertures 2 are provided which prevent any comparatively great transmission of heat from the lower part to the upper part of the tube. The apertures 11 serve to prevent as much as possible a transmission of heat to the switch 10. Another 50 advantage of the device consists in the fact that in consequence of the provision of the loop 21 below the conical part 18 a heat insulating pad is formed of the portion of the 55 hair passing through the loop. With other known apparatus the skin of the head came into touch with the curl-stick at this very spot whereby a disagreeable transmission of heat resulted.

60 In the constructional example illustrated

in Figs. 9-11 the curl-stick comprises a tube 28, into which laterally projecting members 29 are inserted. The members 29 are provided with holes 30 at their parts protruding into the tube, so that all the members 29 can be secured in position by means of a rod 31 penetrating through said holes 30. The members 29 are provided with oblong heads 32. To the lower end of the tube 28 a cord 20 is fastened for forming the loop 21. With this curl-stick the plait of hair can be wound around the former in a more complicated manner than shown in Fig. 8, as the plait 22 on being wound around the tube 28 can also be wound around the members 29. After the hair wound upon the curl-stick 28 has been treated in the heating tube and the latter has been removed, the rod 31 is pulled out of the tube 28 and all the members 29 can be removed so that the plait of hair can readily be taken off the curl-stick.

I claim:

1. In a device of the type described, a tubular curl-stick for winding a plait of hair thereon, and a cord having its one end fixed to said curl-stick and its other end passing through the bore of said tubular curl-stick to form a loop for conveniently clamping one end of the plait of hair to be permanently curled.

2. In a device of the type described, a curl-stick comprising an outer tube and an inner tube, a conical enlargement on one end of the inner tube and frictionally engaging with the bore of the outer tube, a spring interposed between the other ends of said tubes and adapted to press said conical enlargement against said bore, and a cord having its one end fixed to the inner tube and its other end passing through the bore of the inner tube for conveniently clamping one end of the plait of hair to be permanently curled.

3. A device of the type described comprising in combination a tube-shaped curl-stick for winding a plait of hair thereon, a cord having its one end fixed to said curl-stick and its other end passing through said curl-stick to form a loop for clamping one end of the plait of hair, and a heating device comprising an inner tube adapted to take up said curl-stick with the hair wound around it said inner tube being provided with apertures situated in the middle of the length of the tube, at least one heating device, an outer shell distanced from that heating member, the space between the latter and the outer shell being in communication with the surrounding atmosphere.

4. A device of the type described comprising in combination a tube shaped curl-stick for winding a plait of hair thereon, a cord having its one end fixed to said curl-stick and its other end passing through said

- curl-stick to form a loop for clamping one end of the plait of hair, and a heating device comprising an inner tube adapted to take up said curl-stick with hair wound around it, said inner tube being provided with apertures situated in the middle of the length of the tube, at least one heating device, an outer shell distanced from that heating member, the space between the latter and the outer shell being in communication with the surrounding atmosphere, a switch mounted on the top of the heating device and separated from the inner tube and the heating member by means of apertures provided in the former and in said shell.
5. A device of the type described comprising in combination a tube shaped curl-stick for winding a plait of hair thereon, laterally projecting members on said curl-stick around which members the plait of hair can be wound, a cord having its one end fixed to said curl-stick and its other end passing along said curl-stick to form a loop for clamping one end of the plait of hair, and a heating tube adapted to take up said curl-stick with the hair wound around it said inner tube being provided with apertures situated in the middle of the length of the tube, at least one heating device, an outer shell distanced from that heating member, the space between the latter and the outer shell being in communication with the surrounding atmosphere, a switch mounted on the top of the heating device and separated from the inner tube and the heating member by means of apertures provided in the former and in said shell.
6. A device of the type described comprising in combination a tube shaped curl-stick for winding a plait of hair thereon laterally projecting members detachably arranged on said curl-stick around which members the plait of hair can be wound, a cord having its one end fixed to said curl-stick and its other end passing along said curl-stick to form a loop for clamping one end of the plait of hair, and a heating tube adapted to take up said curl-stick with the hair wound around it.
- 10 the outer shell being in communication with the surrounding atmosphere, a switch mounted on the top of the heating device and separated from the inner tube and the heating member by means of apertures provided in the former and in said shell.
- 15 having its one end fixed to said curl-stick and its other end passing along said curl-stick to form a loop for clamping one end of the plait of hair, and a heating tube adapted to take up said curl-stick with the hair wound around it.
- 20 7. A device of the type described comprising in combination a tube shaped curl-stick for winding a plait of hair thereon, laterally projecting members detachably arranged on said curl-stick around which members the plait of hair can be wound, a cord having its one end fixed to said curl-stick and its other end passing through said curl-stick to form a loop for clamping one end of the plait of hair, and a heating device comprising an inner tube adapted to take up said curl-stick with the hair wound around it said inner tube being provided with apertures situated in the middle of the length of the tube, at least one heating device, an outer shell distanced from that heating member, the space between the latter and the outer shell being in communication with the surrounding atmosphere, a switch mounted on the top of the heating device and separated from the inner tube and the heating member by means of apertures provided in the former and in said shell.
